CAR-DOOR HANGER.

1,077,151.

Specification of Letters Patent.

Patented Oct. 28, 1913.

Application filed June 26, 1913. Serial No. 775,915.

To all whom it may concern:

Be it known that I, GEORGE E. MERRITT, a citizen of the United States, residing in the city of Baltimore and State of Maryland, have invented certain new and useful Improvements in Car-Door Hangers; and I do declare the following to be a full, clear, and exact description of the invention, such as will enable others skilled in the art to 10 which it appertains to make and use the same.

This invention relates to car doors, and more especially to those which slide and also move laterally; and the object of the 15 same is to produce an improved hanger or support for the rear edge of the door so that after the latter has been pushed into the door opening it may be moved laterally into line with the car wall.

20 This and other objects are accomplished by the construction hereinafter more fully described and claimed and as shown in the drawings wherein—

Figure 1 is a side elevation of a part of a 25 box car, showing the door as closed; Fig. 2, is a plan view thereof on an enlarged scale, omitting the door. Figs. 3 and 4 are perspective details respectively of the bracket and the bolt hereinafter referred to; Fig. 5 is an enlarged horizontal section on the line 30 5—5 of Fig. 1; Fig. 6 is a cross section on the line 6—6 of Fig. 1.

In the drawings the letter W designates the car wall and T is a track carried by the 35 same near its top and extending parallel therewith as seen at the left in Figs. 1 and 2, but bent slightly and carried obliquely inward over the door opening as usual, D is the door of any suitable type, and C C' are 40 carriages which support said door and by preference have wheels traveling on the track. The carriage near the inner or front edge of the door is mounted on an ordinary bracket B and needs no further description, 45 but when the door is pushed closed its rear edge must be moved laterally into alignment with the car wall W, and hence the connection between this edge of the door and the carriage above it needs peculiarities of construction which are provided by my invention. The frame of this carriage C' has an 50 eye 1 in which is journaled the headed upper end 2 of a bolt 3 which hangs pendent therefrom, and the lower end of the bolt 55 or pin is rigidly secured to one edge of a

substantially triangular plate 4 whose smaller end carries an upstanding stud 5 to constitute a rivet as hereinafter described.

In Fig. 3 is shown a bracket 10 of inverted U-shape whose feet 11 are flattened and 60 pierced with holes 12 for attachment to the outer face of the door, D, whose legs 13 are curved upwardly and outwardly, and whose body 14 is pierced with an eye 15 at one end in which the stud 5 is upset or riveted so 65 that the plate 4 is pivotally connected with the body 14. The latter also has in one edge a notch 16, and upstanding from its outer edge is a finger or stop 17, preferably formed by stamping it from one edge of the 70 plate of strip metal from which the entire bracket is made, and then bending it upward. However, I do not wish to be confined to the material or the exact proportions of which these parts are constructed. 75

The parts are assembled by swiveling the carriage C' around the bolt or pin 3 under its head 2, then passing its plate 4 under the body 14 of the bracket and upsetting the head of the stud 5 in the hole 15 so as to 80 pivot it to the said bracket, and finally securing the latter to the face of the door as shown. The other carriage C being applied to the front corner of the door by an ordinary bracket B, the door is mounted on 85 the track T and slid aside. When now it is closed so that its front edge passes inward over the oblique portion of the track T and enters the door opening, its rear edge may be moved laterally into said door opening by simply pushing upon it. The result 90 is that the door at this edge and the bracket carried by it move inward to the full-lined position shown in Fig. 5, the pivotal point 5 of the plate 4 moves with the bracket, but the bolt or pin 3 remains with the carriage 95 so that the plate is required to turn on its pivot and the lower end of the pin 3 moves out of the notch 16, though the weight of the door is still sustained by the reliable contact of the plate with the under side of the body portion of the bracket for a considerable area as shown. The door now remains locked and the car is carried to its destination. To open the door it is first unlocked 100 and then drawn outward at its rear edge, when a reversal of the operation just described takes place. The weight at the rear edge of the door then comes directly beneath the rear carriage C' and the door is 105 110

2
slid aside as usual, the front carriage C following the track in a manner which is obvious. The stop 17 at the rear edge of the body 14 absolutely prevents the latter from passing out from under the track T, as the stop will strike the track if the door is drawn outward too forcibly or too suddenly.

What is claimed as new is:

- 10 1. A car door hanger consisting of a carriage adapted to travel on a track, a pin swiveled in said carriage, a horizontally disposed plate secured to the lower end of said pin and having an upstanding stud, and a
- 15 bracket of inverted U-shape whose feet are adapted to be secured to the car door, its body being disposed above said plate, pierced with an eye in which said stud is pivoted, and provided in one edge with a

notch for the reception of said pin, for the purpose set forth.

2. A car door hanger consisting of a carriage adapted to travel on a track and having an upright eye, a pin swiveled in said eye and having a head above it, a horizontally disposed triangular plate secured at one edge to the lower end of said pin and having an upstanding stud at its smaller end, and a bracket adapted to be secured to the car door, above said plate and pierced with an eye in which said stud is mounted.

In testimony whereof I have hereunto set my hand in presence of two subscribing witnesses.

GEORGE E. MERRITT.
